COMBINED DETECTOR-AUTOMATIC
VOLUME CONTROL CIRCUITS

Don G. Burnside, Philadelphia, Pa., assignor to
Radio Corporation of America, a corporation
of Delaware

Application November 25, 1932, Serial No. 644,149

11 Claims. (Cl. 250—20)

My present invention relates to improvements in combined detector-automatic volume control circuits, and more particularly to circuits of this type which utilize tubes of the duplex-diode triode type.

There is disclosed by T. M. Shrader in application Serial No. 622,140, filed July 12, 1932, a multiple duty electron discharge tube known as a duplex diode-triode, and designated numerically as of the 55 type. In the said application there have also been disclosed various circuit arrangements for utilizing such a tube as a combined detector-automatic volume control tube; the said circuit arrangements are claimed in Shrader divisional application Serial No. 686,718, filed August 25, 1933. Briefly, it may be stated that such a tube is capable of simultaneous use as a detector or demodulator, an amplifier, and a source of automatic volume control potential. In general, such a tube comprises one, or more, diode sections and a triode section, all disposed within a single tube envelope.

Summarizing the disclosures of the aforementioned applications, it can be stated that there is provided a single electron discharge device which is mechanically a unitary device, but, functionally, is an amplifying triode, and a rectifier having two anodes which are electrically independent of each other and of the amplifier. Such a device has many applications, and has very great flexibility for use with many different kinds of circuits because of the electrical independence of the diodes and the amplifier. The electrodes of the device are enclosed in a single envelope, and are combined in a single mount having a common cathode, with the grid and plate of the amplifier surrounding the cathode near one end, and the rectifier anodes mounted near the other end on independent leads.

One of the main objects of the present invention is to provide a circuit including half wave diode rectification for detection and automatic volume control, the rectification further furnishing the self-bias of the grid of the triode section of a tube of the duplex diode-triode type.

Another important object of the invention is to employ a multiple duty tube of the duplex diode-triode type for half wave diode detection with delay provision together with half wave delayed automatic volume control rectification from a separate diode-anode wherein self-bias from the detector diode is combined with fixed bias.

Still another object of the present invention is to provide a single tube for producing half wave double diode rectification, after amplification of the signal by the triode section of the tube, together with automatic volume control from the diode anodes of the tube.

And still another object of the present invention is to provide a circuit and tube combination, the tube being of the duplex diode-triode type, embodying delayed automatic volume control in order that the ordinary noises present in the receiver may not be reproduced in the absence of the carrier.

And still other objects of the invention are to improve generally the simplicity and efficiency of receivers employing combined detector-automatic volume control-audio frequency amplifier stages, and to particularly provide a receiver of this kind which is not only reliable in operation, but economically manufactured and assembled.

The novel features which I believe to be characteristic of my invention are set forth in particularity in the appended claims, the invention itself, however, as to both its organization and method of operation will best be understood by reference to the following description taken in connection with the drawing in which I have indicated diagrammatically several circuit organizations whereby my invention may be carried into effect.

In the drawing,

Fig. 1 diagrammatically shows a superheterodyne receiver employing a multiple duty tube embodying one form of the present invention;

Fig. 2 shows a portion of the receiver in Fig. 1 embodying a modified form of the invention; and,

Fig. 3 shows a further modification of the invention.

Referring now to the accompanying drawing wherein like reference characters in the different figures designate similar circuit elements, Fig. 1 diagrammatically shows a receiver of the superheterodyne type, wherein the second detector stage includes a circuit and tube combination employing the present invention. Thus, in Fig. 1, there is shown preceding the multiple duty tube 1 the conventional superheterodyne receiver stages. As is well known in the art, such a receiver usually embodies a radio frequency amplifier which is tunable, a local oscillator, a first detector and an intermediate frequency amplifier of one, or more, stages. The output of the intermediate frequency amplifier is impressed upon the second detector, and the audio frequency output of the second detector is supplied to an audio frequency amplifier, and finally a reproducer.

The tube 1 is of the 55 type, that is a duplex diode-triode tube, and includes a plurality of electrodes arranged in the manner described in the aforementioned Shrader application Serial No. 622,140. Such a tube includes a pair of diode sections and a triode section which are independent of each other. The triode section includes an

electron emission electrode 2, such as a unipotential cathode. This cathode preferably comprises a sleeve extending lengthwise of the tube envelope, and contains a heater 3 which is connected to the usual alternating current heating source. The control grid 4 of the triode section is disposed between the cathode 2 and the main anode 5, and in actual construction these three electrodes are co-axial cylinders. The cathode sleeve is longer than the triode assembly; it projects beyond the grid and main anode, and this projecting portion of the cathode sleeve is the cathode of the rectifier or double diode. This has been diagrammatically represented in Fig. 1.

15 Thus, the diode anode D_1 is disposed adjacent one portion of the cathode surface, and the other diode anode D_2 is disposed adjacent another portion of the cathode surface. Both of these cathode portions are independent of the cathode surface which furnishes the electron stream which flows through the grid 4 to the main anode 5. The tube 1 may be said to embody a cathode which is common to both the triode and the two diode anodes, but the diode anodes are positioned outside the electron stream to the triode grid and anode. In actual construction, the diode anodes D_1 and D_2 are disposed adjacent the aforementioned projecting end of the cathode sleeve, and are electrically independent of each other and of the triode section.

These rectifier anodes may be very much smaller than those of the rectifying tubes generally used in receiving sets, since very small currents develop sufficient rectified voltage to give the desired results. The foregoing description of the tube 1 is believed sufficient for the purposes of the present application, inasmuch as, as stated heretofore, the above Shrader application Serial No. 622,140 describes the said tube in great detail, and 40 it is to be clearly understood that this said Shrader disclosure is considered a portion of the present disclosure.

The signal voltage E_0 , which signal voltage in Fig. 1 is the amplified output of the intermediate frequency amplifier, is shown supplied from the secondary of the input transformer M_1 . One end of the secondary winding is connected to the two diode plates D_1 and D_2 in parallel, and the other end is connected through a resistance R_1 , the resistor being shunted by the condenser C_1 , to the cathode lead 6. Rectified current flowing through the resistance R_1 produces across it a direct current voltage which at the M_1 end is negative with respect to the cathode, and an 55 audio frequency voltage, whenever a modulated carrier voltage E_0 is applied to the transformer M_1 .

Radio frequency components are by-passed by the condenser C_1 , while the filter R_2-C_2 permits the passage of the direct current voltage to the path designated A. V. C. (meaning automatic volume control) without a substantial amount of audio frequency voltage. The audio frequency component developed across the resistor R_1 is supplied to the grid 4 of the triode section of tube 1, in proportion to the voltage E_0 and to its degree of modulation. This audio frequency component is amplified, and repeated in the cathode-anode circuit of the triode section of tube 1. The amplified audio frequency component flowing through the resistance R in the circuit of anode 5, which resistor R is in series with the +B terminal of the anode potential source, produces a voltage drop across the re-

sistor R which is supplied to the audio frequency amplifier of the receiver.

The grid 4 is connected to the negative side of the resistor R_1 , and this connection is made through a lead 7 thereto. Preferably, the lead 7 is terminated by an adjustable tap 8. The tap functions as a manual volume control to vary the intensity of audio frequency component delivered to the grid 4 of the triode section of tube 1. The triode section, of course, functions as an audio frequency amplifier prior to the usual audio frequency amplifier of the receiver.

The arrangement in Fig. 1, then, shows a method of use of the tube 1 as a half wave rectifier, the rectifier anodes being the electrodes D_1 and D_2 . Rectification for detector and automatic volume control purposes occurs between the diode plates and the cathode under the influence of a signal modulated alternating voltage. The rectified current flowing through the resistor R_1 not only produces the audio frequency signal for the receiver, but further furnishes the automatic volume control bias which is supplied to the radio frequency amplifier, the first detector and intermediate frequency amplifier stages through the network including the filter R_2-C_2 and the lead 9. It is not necessary to describe the manner in which the negative bias supplied through the automatic volume control network is utilized for automatically controlling the gain of each of the controlled stages, it being believed well known to those skilled in the art how this is accomplished.

It is only necessary to point out that this is usually arranged so that the signal intensity level delivered to the transformer M_1 is maintained substantially uniform as long as signal is being received.

In Fig. 2 the signal voltage E_0 is applied directly only to the diode plate D_1 with the result that the signal is rectified, and applied, as in Fig. 1, to the grid of the triode section by means of coupling condenser C_3 . A desired amount of fixed bias may be applied to the triode grid by means of the source of negative potential E_3 . The diode anode D_1 is electrostatically coupled to the diode anode D_2 by means of condenser C_2 whereby the incoming signal is additionally supplied to the second diode circuit. This signal, when rectified, flows through the resistor R'_2 , and produces a negative voltage at the right hand end thereof, the negative side of the resistor R'_2 being connected by a lead 9' to the automatic volume control filter R_2-C_2 .

By biasing the anode D_1 negatively with respect to the cathode, the bias source being indicated conventionally as E_1 , there is no rectification of the signal until it attains a desired predetermined threshold value. This eliminates most of the ordinary noises present in the receiver which are not desired to be reproduced in the absence of a signal carrier. The source of potential E_2 is so arranged as to bias the plate D_1 negatively by a predetermined amount; this amount necessitating a peak value of signal E_0 greater than the value of the bias furnished by source E_2 before volume control voltage action can start. This produces delayed automatic volume control action.

It will, therefore, be seen that in Fig. 2 there is shown a method of using two rectifier anode plates separately, one being employed for demodulation and the other for automatic volume control. The signal is supplied directly to the plate D_1 . During the positive half cycle recti-

fied current flows through the resistor R_1 by virtue of rectification. A voltage drop occurs across the resistor R_1 , the latter being by-passed by condenser C_1 to afford a low impedance path for the radio or intermediate frequencies. The audio component of rectified voltage across resistor R_1 is impressed on the control grid of tube 1 through the coupling condenser C_3 .

If desired, the direct connection shown in Fig. 1 may be utilized. By biasing the plate D_1 negatively with respect to the cathode, the more or less constant tube and circuit "noise voltage" may be eliminated or reduced. The bias value of source E_1 may be such that it is just above the noise level on the demodulator plate D_1 . This, then, serves as a noise suppressor device which functions to render the receiver demodulator inoperative until a predetermined ratio of signal to noise voltage is exceeded.

The capacitor C_2 is of such a magnitude that it passes to the rectifier anode D_2 the signal on plate D_1 with but little attenuation. The section including plate D_2 thus becomes an independent rectifier so far as direct current is concerned. The resistor R_2 , being the external resistor for this rectifier, has current flowing through it when the plate D_2 is positive. This direct current component of rectified voltage across resistor R_2 is employed for automatic volume control. The generation of automatic volume control voltage may be delayed to any desired extent by application of the negative voltage from source E_2 to the plate D_2 . In this event the peak value of signal must exceed the negative bias on plate D_2 before any volume control action can be initiated.

The source E_2 , therefore, represents a device for securing delayed automatic volume control, and is a device which functions independently of the noise suppressor device which governs the point at which demodulation can commence. Instead of a resistor R being disposed in the circuit of the main anode of tube 1, there is shown an auto-transformer L , the drop across which is employed for audio frequency amplification. Of course, this auto-transformer may also be the primary of a transformer of the well known type.

Another modification of the invention is shown in Fig. 3 wherein the signal transmitted through the transformer M_1 , this signal either being at radio or intermediate frequency, is amplified prior to rectification, which is contrary to the procedure disclosed in Figs. 1 and 2. The high frequency voltage, amplified by the triode section of tube 1, is impressed on the rectifier anodes D_1 and D_2 by means of the capacitor C'_1 , which capacitor is connected between the main anode 5 and the diode anodes D_1 and D_2 . The capacitor C'_1 is of such a size that while its impedance to the high frequency currents is low, it has a relatively high impedance to audio frequencies. Of course, in place of C'_1 there can be used any other type coupling as an *r.f.* or *i.f.* transformer. A form of shunt feed for the triode plate 5 is used, the radio frequency choke L_1 preventing loss of high frequency voltage, and, at the same time, permitting direct current voltage to be supplied to the plate.

The amplified radio frequency or intermediate frequency voltage is impressed on plates D_1 and D_2 together, or separately in case independent use of each is desired; this causes rectification to occur. The resulting potential drop across resistor R'_1 is used, in the case of the direct component of rectified voltage, for auto-

matic volume control through a suitable filter, and in the case of audio component of the rectified voltage, the potential drop across resistor R'_1 may be used for further voltage amplification, or for power amplification. The automatic volume control voltage may be taken from the point indicated, that is at the negative end of the resistor R'_1 , and the audio voltage E_1 may be taken from across the resistor R'_1 or any desired part thereof.

It will, therefore, be seen that the circuits of tube 1 in Fig. 3 are so arranged that the incoming signal is applied directly between the cathode and grid of the triode section, the source E_4 furnishing negative grid bias for the grid of tube 1 when this is desired. The amplified voltage from the main plate circuit is delivered through the condenser C'_1 to the diode plates D_1 and D_2 in parallel, the direct current flowing through the resistor R'_1 under the influence of the signal voltage producing a difference of potential. The direct current component of the potential drop across R'_1 is led off to the automatic volume control circuit as employed above, and the audio component may be taken off across the resistor R'_1 in the usual manner.

While I have indicated and described several systems for carrying my invention into effect, it will be apparent to one skilled in the art that my invention is by no means limited to the particular organizations shown and described, but that many modifications may be made without departing from the scope of my invention as set forth in the appended claims.

What I claim is:

1. The combination with an electron discharge tube comprising an envelope enclosing an electron discharge section including at least a cathode, grid and plate, and a rectifier having two independent anodes, of an oscillatory circuit having one side thereof connected for radio frequencies to both said anodes, and its other side connected to said cathode, a resistor disposed in said other side, a connection between the grid of said tube and a point of said resistor, a fixed bias source connected between said grid and said cathode, an automatic volume control path connected to one of said anodes, and a volume control bias resistor connected between said path and said cathode.

2. The combination with an electron discharge tube comprising an envelope enclosing an electron discharge section including at least a cathode, grid and plate, and a rectifier having two independent anodes, of an oscillatory circuit having one side thereof connected for radio frequencies to both said anodes, and its other side connected to said cathode, a resistor disposed in said other side, a connection between the grid of said tube and a point of said resistor, a fixed bias source connected between said grid and said cathode, an automatic volume control path connected to one of said anodes, a volume control bias resistor connected between said path and said cathode, and means connected to the other of said anodes for preventing demodulation whenever little or no signal carrier is impressed on said oscillatory circuit.

3. The combination with an electron discharge tube comprising an envelope enclosing an electron discharge section including at least a cathode, grid and plate, and a rectifier having two independent anodes, of an oscillatory circuit having one side thereof connected for radio frequencies to both said anodes, and its other side connected to said cathode, a resistor disposed in said other side, a connection between the grid of said tube

- and a point of said resistor, a fixed bias source connected between said grid and said cathode, an automatic volume control path connected to one of said anodes, a volume control bias resistor connected between said path and said cathode, means connected to said volume control path and anode for delaying the automatic volume control action until the signal carrier impressed on said oscillatory circuit attains a predetermined threshold value.
4. The combination with an electron discharge tube comprising an envelope enclosing an electron discharge section including at least a cathode, grid and plate, and a rectifier having two independent anodes, of an oscillatory circuit having one side thereof connected for radio frequencies to both said anodes, and its other side connected to said cathode, a resistor disposed in said other side, a connection between the grid of said tube and a point of said resistor, a fixed bias source connected between said grid and said cathode, an automatic volume control path connected to one of said anodes, a volume control bias resistor connected between said path and said cathode, means connected to the other of said anodes for preventing demodulation whenever little or no signal carrier is impressed on said oscillatory circuit, and means connected to said volume control path and anode for delaying the automatic volume control action until the signal carrier impressed on said oscillatory circuit attains a predetermined threshold value.
5. In combination with a source of signal modulated radio frequency carrier energy, a multiple function tube including a cathode, a signal grid, main anode and a diode anode, a signal input circuit coupling said source to said diode anode and cathode, an impedance in said input circuit across which the said carrier energy develops an audio frequency potential, a connection from said grid to said impedance, an audio frequency network coupled to said main anode, signal level control means independent of the circuit including said impedance responsive to signals impressed on said input circuit, for producing solely a direct current potential varying in magnitude with signal amplitude, and means connected to said input circuit for maintaining the diode anode negative with respect to the cathode until the impressed carrier energy increases above a predetermined intensity level.
6. In combination with a source of signal modulated radio frequency carrier energy, a multiple function tube including a cathode, a signal grid, main anode and a diode anode, a signal input circuit coupling said source to said diode anode and cathode, a diode rectifier network coupled to said input circuit, said network including an impedance, and an automatic gain control connection connected to a point on said impedance, an impedance in said input circuit across which the said carrier energy develops an audio frequency potential, a connection from said grid to said last impedance, an audio frequency network coupled to said main anode, and means connected to said input circuit for maintaining the diode anode negative with respect to the cathode until the impressed carrier energy increases above a predetermined intensity level.
7. In a radio receiver, a multiple duty tube provided with at least a cathode, a signal grid, a main anode, and two diode anodes, a signal input circuit connected between one of the diode anodes and said cathode, said other diode anode being connected to said input circuit, a resistor in said

input circuit, a second resistor connected between the cathode and the said other diode anode, a direct current connection to a point of negative potential on said second resistor, a connection between said grid and a point on said first resistor, a load circuit connected to said main anode, and means for biasing said diode anodes negatively with respect to said cathode.

8. In a radio receiver, a multiple duty tube provided with at least a cathode, a signal grid, a main anode, and two diode anodes, a signal input circuit connected between one of the diode anodes and said cathode, said other diode anode being connected to said input circuit, a resistor in said input circuit, a second resistor connected between the cathode and the said other diode anode, a direct current connection to a point of negative potential on said second resistor, a connection between said grid and a point on said first resistor, a load circuit connected to said main anode, and independent means for biasing said diode anodes negatively with respect to said cathode in the absence of signals.

9. In a radio receiver, a multiple duty tube provided with at least a cathode, a signal grid, a main anode, and two diode anodes, a signal input circuit connected between one of the diode anodes and said cathode, said other diode anode being connected to said input circuit, a resistor in said input circuit, a second resistor connected between the cathode and the said other diode anode, a direct current connection to a point of negative potential on said second resistor, a connection between said grid and a point on said first resistor, a load circuit connected to said main anode, means for biasing the grid negatively with respect to said cathode, and means for biasing said diode anodes negatively with respect to said cathode.

10. In a radio receiver, a multiple duty tube provided with at least a cathode, a signal grid, a main anode, and two diode anodes, said diode anodes being outside the electron stream to said grid and main anode, a signal input circuit connected between one of the diode anodes and said cathode, said other diode anode being connected to said input circuit, a resistor in said input circuit, a second resistor connected between the cathode and the said other diode anode, a direct current connection to a point of negative potential on said second resistor, a connection between said grid and a point on said first resistor, a load circuit connected to said main anode, and means for biasing said diode anodes negatively with respect to said cathode.

11. In combination with an electron discharge tube of a type including at least a cathode and two anodes and said cathode providing independent electron streams to said anodes, a source of modulated radio frequency carrier energy, an input circuit, tuned to the carrier frequency, connected between said cathode and one of the anodes, an impedance in said circuit with said input circuit whereby a signal detector network is provided, a second impedance in circuit with said cathode and the second anode and providing a carrier energy rectifier network, an automatic gain control connection to a point on said second impedance, means operatively associated with the detector network for preventing detection until a predetermined carrier amplitude is attained, and means operatively associated with the rectifier network for delaying the gain control action until a desired carrier amplitude is attained.
